UNITED STATES PATENT OFFICE.

FRANK OLECHNOWICZ, OF MINEOLA, NEW YORK.

HAT-PIN GUARD.

1,092,536.

Specification of Letters Patent.

Patented Apr. 7, 1914.

Application filed July 29, 1913. Serial No. 781,862.

To all whom it may concern:

Be it known that I, FRANK OLECHNOWICZ, a subject of the Czar of Russia, residing at Mineola, in the county of Nassau and State 5 of New York, have invented certain new and useful Improvements in Hat-Pin Guards, of which the following is a specification.

This invention relates to hat pin guards. 10 The object of the invention is to provide a neat and effective article of this character, which will not only positively protect the pin from possibility of inflicting injury, but will also prevent loss of the pin.

15 With the above and other objects in view, as will appear as the nature of the invention is better understood, the same consists, generally stated, in a hat pin guard comprising a split sheath, the opposing faces of the members 20 of which are provided with channels or grooves to receive the point of the pin, combined with means for clamping the sheath members around the pin in such manner as to shield its point, and at the same time to 25 lock the guard upon the pin against danger of accidental separation therefrom.

The invention consists further in the various novel details of construction of a hat pin guard as will be hereinafter fully 30 described and claimed.

In the accompanying drawing forming a part of this specification, and in which like characters of reference indicate corresponding parts: Figure 1 is a view in side 35 elevation exhibiting a hat pin with the guard of the present invention applied thereto. Fig. 2 is an enlarged detail view, partly in section, of the guard, showing the same applied to a pin point. Fig. 3 is a view similar to Fig. 1 showing the parts of 40 the sheath distended to receive the pin. Fig. 4 is a transverse sectional view taken on the line 4—4, Fig. 2, and looking in the direction of the arrow thereon. Fig. 5 is a perspective detail view of the sheath. Fig. 6 is a similar view of the clamping nut, and, Fig. 7 is a collective detail view, in perspective, exhibiting certain parts of the guard.

Referring to the drawing, and more particularly to Figs. 2, 3, and 5, there is exhibited one form of sheath that may be employed in conjunction with the present invention, although as will be obvious, the precise details of this construction may be 55 varied without departing from the spirit of the invention. The sheath comprises two

straight members 1 and 2, and an approximately ovoid hollow head 3, forming an integral continuation of the legs or members 1 and 2. The latter are externally threaded 60 and each is provided at its lower end with an out-turned extension 4 constituting a stop and on its inner face with a channel 5, which is preferably of semi-rectangular contour in cross-section, in order, that when 65 the two legs or members are assembled, as shown in Fig. 2, a pronounced gripping action will be secured upon the pin P, which will serve to lock the guard thereto. Disposed upon the lower end portion of the 70 two members is a thimble 6 which is provided with a down-turned flange 7 that is designed to receive the stops 4, and thus retain the thimble in position, it being understood that the legs 1 and 2 normally flex 75 outward, so that the stops would ordinarily rest beneath the horizontal member of the flange. In order positively to prevent disconnection of the thimble from the sheath legs, a guide 8 is provided in the nature of 80 a tapered sided member provided with a central orifice 9 to receive and guide the pin between the legs, a split locking ring 10 inserted between the walls of the guide and the thimble, and bearing upon the upper 85 side of the flange 7 serving to prevent positively, disconnection of the guide from the thimble, and likewise the separation of the thimble from the sheath.

As will be noted by reference to Fig. 3, 90 the opposed walls of the legs 1 and 2, when the guard is not positioned upon the pin, assume an angular position presenting a tapered opening corresponding to the taper of the point portion of the pin, and in order 95 to bring the two legs into contact with the pin, a winged clamping nut 11 is provided which, when moved to the position shown in Fig. 3 will cause the legs 1 and 2 firmly to impinge against the pin, and thus lock 100 the guard securely thereon. While it will ordinarily be preferred to employ a winged clamping nut as shown, it is to be understood that if preferred, the wings may be omitted, and the body-portion of the nut 105 knurled, and obtain the same result as that secured by the arrangement shown.

It will be noted that by the arrangement of the parts, a firm gripping action can be obtained between the legs and the pin, so 110 that positive prevention of loss of the guard will be obviated and likewise that of the

pin, and also that the pin point will be positively shielded, so that danger of inflicting injury will be positively precluded.

What is claimed is:—

- 5 A hat pin guard, comprising an externally-threaded split sheath provided with outwardly projecting stops located at the lower end of said sheath, a clamping nut upon said sheath, a thimble having an end flange to engage said stops, a guide through

which the pin is adapted to extend, and a locking ring interposed between said guide and thimble, and supported upon the flanged end of the latter.

In testimony whereof I affix my signature in presence of two witnesses.

FRANK OLECHNOWICZ.

Witnesses:

JOHN ZEGLISKY,
FRACO. SACCO.
